UNITED STATES PATENT OFFICE.

HERBERT WALDO BROWN, OF ASHLAND, OHIO.

FOCUSING DEVICE FOR HEADLIGHTS.

1,386,312.

Specification of Letters Patent.

Patented Aug. 2, 1921.

Application filed April 14, 1920. Serial No. 373,798.

To all whom it may concern:

Be it known that I, HERBERT W. BROWN, a citizen of the United States, residing at Ashland, in the county of Ashland and 5 State of Ohio, have invented a new and useful Focusing Device for Headlights, of which the following is a specification.

This invention has reference to focusing devices for automobile electric headlights 10 and its object is to provide easily and quickly actuated means for adjusting the electric bulb, commonly employed in automobile headlights, accurately and without the aid of tools.

15 In accordance with the invention the headlight is provided with the customary reflector and axial sleeve for holding the lamp receptacle, but the receptacle and sleeve are somewhat modified in that there 20 is provided a clip or lock for adjustably holding the receptacle in the sleeve or collar whereby the lamp may be moved axially and properly centered into any one of a large number of positions and they are held 25 without the use of adjusting screws or set screws to hold the lamp socket properly located in the optical axis of the reflector.

The invention will be best understood 30 from a consideration of the following detailed description taken in connection with the accompanying drawing forming part of this specification, with the understanding, however, that the invention is not confined 35 to any strict conformity with the showing in the drawing, but may be changed and modified so long as such changes and modifications mark no material departure from the salient features of the invention as expressed in the appended claims.

40 In the drawings,

Figure 1 is a rear elevation of the reflector showing the outer shell of the lamp receptacle in cross section in substantially the plane of the clip or lock.

45 Fig. 2 is a front to rear elevation with some parts in section of the structure shown in Fig. 1.

Referring to the drawings there is shown 50 a bowl-shaped reflector body 1, which may be of usual construction and hence requires no special description. At the base of the reflector there is secured a sleeve 2 having an opposite ring 3 from which there is a continuation for entering the reflector and 55 there expanded so that the reflector and

sleeve are securely fastened together. The sleeve is shaped to receive a socket 5 arranged in the usual manner to in turn receive the base 6 of an electric lamp bulb 7. The socket 5 is formed in the usual manner 60 with bayonet slots in which are introduced the usual pins to secure the lamp base 6 in the socket 5.

In order to limit the entrance of the socket 5 into the sleeve 2, the latter has out-turned 65 tongues 8 so positioned as to engage the sleeve and thereby prevent the introduction of the socket into the sleeve beyond a certain distance. The socket 5 is provided with a back contact carrier 9, which may be 70 of usual construction, and this carrier is provided with a bore 10 for the reception of an electric conductor 11 held in the back contact carrier by a set screw 12, or in other appropriate manner. Applied to the carrier 75 9 is a ring 13 which is held to the back contact carrier by the conductor 11 and is of such size as to engage the rear or outer end of the sleeve 2, thus preventing the movement of the socket 5 into the reflector beyond a determined distance. Provision is thus made for preventing escape of the lamp 80 socket from either end of the sleeve but at the same time permitting a limited adjustment of the socket and the lamp carried thereby longitudinally of the optical axis 85 of the lamp and reflector.

On opposite sides but preferably, though not necessarily, to one side of the longitudinal diametric plane of the sleeve are lips 90 14 which may be conveniently pressed out of the sleeve 2, forming thereby sockets or receptacles for ends 15, with an elliptical spring 16 formed of a piece of spring wire with terminals 17 cut off substantially square 95 whereby to form edges which will readily bite into the surface of the socket 5. In this manner the terminals or ends 17 form cutting edges which enter the outer surface of the socket 5, particularly as the socket 100 is usually made of some hard material like brass, and with the spring 16 of harder material like steel, the tendency of the spring 16 is to bite into the socket 5 is quite pronounced. By properly proportioning the 105 parts the spring 16 may be spread sufficiently to permit the ends 17 thereof to enter the sockets 14 and press with requisite force against the socket 5. The spring 16, therefore, constitutes an elastic or spring 110

clip suitably strong to hold the socket 5 in any position of adjustment in the sleeve 2 against displacement by such shocks or jars as may occur in the use of the headlight 5 but which will yield to designedly applied forces whereby the socket 5, with a bulb 7 carried thereby may be adjusted at the will of an operator. Such adjustment may be performed by pushing the bulb 7 into or 10 out of the socket 5 from the reflector end thereof. At times the adjustment may be more easily performed by imparting a twisting movement to the lamp and its socket, thus making the adjustment easier, especially if performed from the rear of the 15 reflector. Whatever the procedure the socket will remain fixed in the adjusted position to which it is moved and will hold such position against all disturbing forces, other 20 than those purposely applied. The structure provides accurate and easily manipulated means whereby the focusing of the lamp is more readily and accurately performed than is possible by the use of adjusting screws or by the use of step devices, 25 for the adjustment permits of practically infinitesimal steps both lengthwise and circumferentially of the reflector.

This invention is an improvement upon 30 the bulb focusing device for automobile electric headlights for which I filed application, Serial No. 368,567, on March 25, 1920, but which application omits certain advantageous features herein disclosed, although

containing some features in common with 35 this invention.

What is claimed is:

1. A bulb focusing device for automobile electric headlights employing a reflector body with a sleeve at its basic end, comprising a socket for an electric headlight bulb adapted to the interior of the sleeve, and an elastic clip or holding means carried by the sleeve in engagement with the outer wall of the socket, the sleeve being provided with 40 circumferentially spaced passages for the ends of the clip, with said passages having outwardly directed lips for holding and guiding the ends of the spring clip and directing them into biting engagement with 45 the lamp socket when in the sleeve.

2. A bulb focusing device for automobile electric headlights provided with a reflector bowl or body and a sleeve at the basic end thereof, comprising a socket for the electric 55 bulb adapted to the sleeve for movement longitudinally and circumferentially with relation thereto, and the sleeve having passages leading to the interior thereof, and lips covering said passages, a clip or holding device comprising an appropriately bent piece of spring wire with square cut ends 60 entering the passages beneath the lips and engaging the outer surface of the socket by means of the square cut ends.

In testimony that I claim the foregoing as my own, I have hereto affixed my signature.

HERBERT WALDO BROWN.
